R. G. WOODWARD & C. MCNEIL.

TUCK FORMING ATTACHMENT FOR SEWING MACHINES.

APPLICATION FILED APR. 16, 1901.

UNITED STATES PATENT OFFICE.

RUSSEL G. WOODWARD, OF WAUKEGAN, AND CHESTER McNEIL, OF CHICAGO, ILLINOIS, ASSIGNORS TO THE UNION SPECIAL SEWING MACHINE CO., OF CHICAGO, ILLINOIS, A CORPORATION OF ILLINOIS.

TUCK-FORMING ATTACHMENT FOR SEWING-MACHINES.

No. 821,774.

Specification of Letters Patent.

Patented May 29, 1906.

Application filed April 16, 1901. Serial No. 56,063.

To all whom it may concern:

Be it known that we, RUSSEL G. WOODWARD, residing at Waukegan, in the county of Lake, and CHESTER McNEIL, residing at Chicago, in the county of Cook, State of Illinois, citizens of the United States, have invented certain new and useful Improvements in Tuck-Forming Attachments for Sewing-Machines, of which the following is a description, reference being had to the accompanying drawings and to the letters of reference marked thereon.

Our invention relates to an improvement in sewing-machines; and the especial object 15 of said invention is to provide a machine adapted to form box-plaiting on the face of fabric.

As herein illustrated, the machine comprises four needles arranged in sets of two 20 each, the sets being arranged so that the plane containing them is oblique respecting the line of feed, a single looper coöperating with the two needles of each set to form the stitches, the machine being substantially 25 similar to that shown in Patent No. 506,538, issued to the Union Special Sewing Machine Company and known as the "Union Special Multiple-Needle Machine."

The invention consists, primarily, of a sewing-machine having a plurality of needles, a 30 presser-foot and throat-plate having complementary fins and grooves whereby a series of parallel continuous tucks is formed in the fabric, complementary stitch-forming mechanism coöperating with the needles to hold the 35 ridges or tucks permanently in the fabric, and means for flattening out the tucks.

Secondly, the invention consists of a sewing-machine having a plurality of needles, a 40 presser-foot and throat-plate having complementary fins and grooves whereby a series of parallel continuous tucks is formed in the fabric, complementary stitch-forming mechanism coöperating with the needles to hold the 45 ridges or tucks permanently in the fabric, and means in rear of the needles for flattening out the tucks.

Thirdly, the invention consists of a sewing-machine having a plurality of sets of needles, 50 each set composed of two or more needles set abreast and the sets arranged so that a plane containing them is oblique to the line of feed, with a presser-foot and throat-plate having

complementary fins and grooves for forming a series of continuous parallel ridges in the fabric between the needles of each set, complementary stitch-forming mechanism coöperating with the needles to hold the ridges permanently in the fabric, and means in rear of the needles for turning over or flattening out the ridges forming a plait.

Fourthly, it consists of an arrangement of needles, loopers, presser-foot, and throat-plate with means for turning over the ridges of the fabric in opposite directions, thus forming a box-plait.

Finally, the invention consists of the combination of presser-foot and throat-plate of suitable construction and in various details of construction and arrangements of parts, 70 all as hereinafter described, and referred to in the appended claims.

The invention is illustrated in the accompanying drawings, in which—

Figure 1 is a perspective view of a portion 75 of a sewing-machine embodying our invention. Fig. 2 is a perspective view of the presser-foot and throat-plate detached. Fig. 3 is a cross-section through the presser-foot and throat-plate. Fig. 4 is a sectional view 80 showing the work before the ridges are bent down to form the box-plait. Fig. 5 is a similar view showing the work after the formation of the box-plait; and Fig. 6 is a detached view of a presser-foot and throat-plate, showing a modified form of our invention.

In the drawings the parts of the sewing-machine proper are of the well-known type illustrated in patent above mentioned and need not be herein specifically referred to.

A represents the needle-bar, which is herein shown as provided with two sets of needles arranged in pairs *a a*, *b b*, the needles of each set being arranged abreast, but the sets being arranged in a plane oblique to the line of feed, whereby a plurality of air-tucks close together may be made permanently in the fabric. Coöperating with the needles *a a*, *b b*, respectively, are loopers *c d*, each carrying a single under thread coöperating with 90 the loops of needle-thread to form stitches.

B represents the throat-plate of the machine, having openings *e e*, arranged so that a line joining them is oblique respecting the line of feed and through which the needles *a a*, *b b* respectively pass. Extending over

the forward part of the throat-plate and intersecting each opening *e* are raised fins or plates *f f'*, fitting in grooves *g g* in the under side of the presser-foot *C*. When the material is inserted between the presser-foot and throat-plate and the presser-foot depressed, narrow ridges or tucks *h* are formed in the material and secured by the needle-threads and coöperating under threads, thus making 10 continuous and permanently-sewed ridges or tucks. Back of the needle-openings *i* in the presser-foot *C* the latter is cut away, as shown at *k l*, the sides of the openings being beveled, as at *m*, and when the tuck passes 15 from the needles into the openings and against the lower edges of the openings *k l* the tucks are bent down flat and oppositely turned, as shown in Fig. 4, making a box-plait. The presser-foot has a forward projection *n*, which travels between the tucks. 20 It will be noticed that the fin or plate *f'* is slightly higher than the fin or plate *f*, the purpose of this being that the forward set of needles *a a* pass through the goods first 25 and draw the goods across the fin *f'* and tend to lower the ridge or tuck, and for this purpose the fin *f'* is made higher in order not to draw down the goods too far and thus lower the ridge formed by fin *f'* below the 30 level of that formed by *f*.

In Fig. 6 a modified form of our invention is illustrated, in which two needles only are used, *a b*, set so that a line joining them is oblique respecting the line of feed, and the 35 openings *k l* in the presser-foot are in advance of the needles, the ribs on the throat-plate being provided with guiding-tongues *m n*, projecting out into the cut-out portions *k l*, so as to aid in turning the tuck over, and 40 in this event the tuck is turned before stitching. In this way the stitches will pass through the base of the tucks, and we consider such a modification within the scope 45 of our broad invention. This modification, however, forms a portion of the subject-matter of another application, filed by us on the 5th day of January, 1905, Serial No. 239,774.

Various minor modifications and changes 50 may be made without departing from the spirit of our invention.

Having thus described our invention, what we claim, and desire to secure by Letters Patent, is—

55 1. A sewing-machine having a plurality of needles, a presser-foot and throat-plate having complementary ridges, fins or plates, and grooves, whereby a series of parallel continuous tucks is formed in the fabric, complementary stitch-forming mechanism coöperating with the needles to hold the ridges or tucks permanently in the fabric and 60 means on the presser-foot for flattening out the ridges or tucks said needles being arranged in pairs, the needles of each pair op-

erating upon opposite sides of the fins and grooves; substantially as described.

2. A sewing-machine having a plurality of needles, a presser-foot and throat-plate having complementary ridges, fins or plates, and 70 grooves, whereby a series of parallel continuous tucks is formed in the fabric, complementary stitch-forming mechanism coöperating with the needles to hold the ridges or tucks permanently in the fabric and means on the presser-foot in rear of the needles for flattening out the ridges said needles being arranged in pairs, the needles of each pair operating upon opposite sides of the fins and grooves; substantially as de- 75 scribed.

3. A sewing-machine having a plurality of sets of needles, each set composed of two or more needles set abreast and the sets arranged so that the plane containing them is 85 oblique to line of feed, a presser-foot and throat-plate having complementary ridges, fins, or plates, and grooves, whereby a series of parallel continuous tucks is formed in the fabric, complementary stitch-forming mech- 90 anism coöperating with the needles to hold the ridges or tucks permanently in the fabric and means on the presser-foot in rear of the needles for flattening out the ridges; sub- 95 substantially as described.

4. A sewing-machine having a plurality of sets of needles, each set composed of two or more needles set abreast and the sets arranged so that a plane containing them is oblique to the line of feed, a presser-foot and 100 throat-plate having complementary ridges, fins or plates, and grooves, whereby a series of parallel continuous tucks is formed in the fabric, complementary stitch-forming mech- 105 anism coöperating with the needles to hold the ridges or tucks permanently in the fabric and means on the presser-foot in rear of the needles for flattening out the ridges in oppo- 110 site directions, thus forming a box-plait; sub- substantially as described.

5. A sewing-machine provided with a plu- 115 rality of needles and complementary stitch-forming mechanism, a presser-foot and throat-plate having coöperating fins and grooves to form ridges in the fabric, said presser-foot being cut away in rear of the needle-openings and arranged to deflect the ridges in the fabric; substantially as de- 120 scribed.

6. A sewing-machine provided with a plu- 120 rality of needles and with a presser-foot hav- 125 ing a series of grooves in its under side, a throat-plate having fins or ridges registering with said grooves and means on said presser- foot in rear of said needles for deflecting the tucks in the fabric; substantially as de- 130 scribed.

7. A sewing-machine, provided with a presser-foot, having a series of grooves in its under side, a throat-plate having fins or 130

ridges registering with said grooves and opening into the needle-openings and means on said presser-foot in rear of the needles for deflecting the tucks in the fabric; substantially 5 as described.

8. In a sewing-machine provided with a presser-foot having a series of grooves on its under side, a throat-plate having fins or ridges registering with said grooves, one of 10 said fins or ridges being higher than the other; substantially as described.

9. In a sewing-machine provided with a presser-foot having a plurality of grooves on its under side, one of said grooves being 15 deeper than the other, a throat-plate having a plurality of fins or ridges of varying heights registering with said grooves; substantially as described.

10. In a sewing-machine provided with a 20 plurality of needles arranged so that a line joining them is oblique to the line of feed, and complemental stitch-forming mechanism, a presser-foot and throat-plate having coöperating fins and grooves, so arranged 25 that a line joining the rear ends of said fins and grooves respectively is substantially parallel with the line joining the needles; substantially as described.

11. In a sewing-machine provided with a

presser-foot having grooves on its under side 30 and also having suitable needle-openings, a throat-plate having ribs registering with said grooves and having suitable needle-openings registering with those in the presser-foot, 35 said needle-openings being arranged obliquely to the line of feed, and a plurality of cut-out spaces also arranged obliquely to the line of feed; substantially as described.

12. In a sewing-machine having suitable 40 stitch-forming mechanism, and a presser-foot and throat-plate, said presser-foot and throat-plate being provided with complemental grooves and ridges for forming a tuck in the fabric and the stitch-forming mechanism including a pair of needles reciprocating 45 upon opposite sides of the tuck, whereby the same may be permanently held in place, means for deflecting the tuck in rear of the stitch-forming mechanism to lie in a horizontal plane; substantially as described. 50

In testimony whereof we affix our signatures in presence of two witnesses.

RUSSEL G. WOODWARD.
CHESTER McNEIL.
